- ing mechanism, and opposing decorticating members that extend longitudinally of the machine and which are moved downwardly away from the stock holding mechanism when in engagement with the stock, mechanism for propelling the opposing decorticating members away from the stock holding mechanism, and mechanism comprising an intermittent gearing between the mechanism for propelling the decorticating members on the one hand and the feeding mechanism on the other so that an intermittent movement can be imparted to the feeding mechanism.
4. In a machine of the class described the combination of stock holding mechanism comprising stock holding grippers, feeding mechanism comprising an endless chain and carrying grippers arranged to engage the upper end of the stock so as to convey it in position to be held by the stock holding grippers, mechanism for removing pulp and waste from the stock as the latter depends from the stock holding grippers which engages the upper portion of the stock below a carrying gripper, and common mechanism between the pulp and waste removing mechanism, the stock holding gripper and the feeding mechanism, said common mechanism comprising a cam for actuating the stock holding gripper and an intermittent gearing for imparting an intermittent movement to the feeding mechanism.
5. In a machine of the class described, a feeding mechanism comprising a pair of sprockets, an endless chain carried and operated by said sprockets, a pair of longitudinally extending fixed guideways located on opposite sides of the chain, carrying grippers connected to said chain, said carrying grippers having longitudinally extending jaws, and laterally and oppositely extending portions which engage said guideways so as to retain the said jaws in the proper position as they are moved longitudinally by the chain, said jaws being spring pressed toward each other and one of them being provided with a laterally extending arm whereby said jaws can be separated.
6. In a machine of the class described, a pair of sprockets mounted on shafts carried in bearings on the frame, an endless chain in mesh with said sprockets, longitudinally extending guiding or holding members located on opposite sides of said chain, carrying grippers secured to said chain, said carrying grippers comprising spring pressed longitudinally extending jaws and a laterally extending handle for opening the jaws against the pressure of the spring, said carrying grippers having portions which engage the said oppositely disposed guideways so that when the handle is pressed the gripper will be retained in its proper position.
7. A machine of the class described comprising a frame, a feeding mechanism carried thereby, mechanism for removing pulp and waste from the fiber in the stock being treated, and mechanism whereby the pulp and waste removing mechanism and the feeding mechanism will operate in timed relation with respect to each other, the feeding mechanism comprising a series of longitudinally extending carrying grippers which are connected to an endless chain which is also a part of the feeding mechanism, there being located holding members on opposite sides of the chain, longitudinally extending members for holding the carrying grippers in position and a cam in the path of the carrying grippers for causing the latter to open at predetermined times while the grippers are being moved longitudinally.
8. In a machine of the class described, the combination of an endless chain, sprockets upon which the chain is carried, a series of carrying grippers secured to the chain, each of said grippers having longitudinally extending jaws, fixed longitudinally extending ways or guides that are engaged by portions of the carrying grippers and serve as means for maintaining the carrying grippers in the proper position, and means located in the path of the carrying grippers for causing one of said jaws to be moved laterally relative to the companion jaws while in engagement with said guideways at a time when the grippers reach a certain place in their travel.
9. In a machine of the class described, the combination of holding grippers and a feeding mechanism comprising an endless chain having connected thereto a series of stock carrying grippers, the machine also comprising members for guiding or holding the stock carrying grippers, and mechanism for automatically opening said stock carrying grippers and constructed so as to permit said stock carrying grippers to be closed upon the stock when desired.
10. In a machine of the class described a pair of opposing stock engaging members which are propelled downwardly by endless conveying chains when the said members are in engagement with the stock, said endless chains also carrying below the stock engaging members a pair of aprons which are located between the chains and travel therewith for protecting the chains from the substance removed from the stock being operated upon.
11. A fiber isolating machine comprising a main frame, a stock holding gripper supported on the upper portion of the frame, stock feeding mechanism comprising stock carrying grippers that travel above the jaws of the holding gripper, mechanism comprising decorticating members which engage opposite sides of the stock when the

CHARLES EDWARD HAND, OF ST. CATHARINES, ONTARIO, CANADA.

COMPASSES OR DIVIDERS.

1,145,016.

Specification of Letters Patent.

Patented July 6, 1915.

Application filed May 14, 1911, Serial No. 625,095. Renewed November 21, 1914. Serial No. 873,283.

To all whom it may concern:

Be it known that I, CHARLES EDWARD HAND, a subject of the King of Great Britain, residing at St. Catharines, in the county 5 of Lincoln, in the Province of Ontario, Canada, have invented certain new and useful Improvements in Compasses or Dividers, of which the following is a specification.

My invention relates to improvements in 10 compasses or dividers, and relates more particularly to improving the construction of the compass or dividers disclosed in my allowed United States application, filed October 1, 1909 under Number 520,582, and in 15 my United States Patent Number 920,461, dated May 4, 1909. Now in these compasses or dividers, as well as in connection with the present invention, the marking elements will always be held substantially perpendicular 20 to the work no matter in what operative position the legs of the compass may be, and more specifically stated, the objects of the present invention are firstly: to provide a particular construction of yoke situate in the 25 head of the compass or dividers so that by means of the co-action therewith of the pressure screw and nut, the upper ends of the link-members can be gripped between the yoke plates of the yoke and so keep the 30 links under tension as well as the legs of the tool. In constructing the yoke plates, they are made so that the same will not grip the link-members below their upper ends; secondly: to pivot the upper end of 35 each link-member on each side in the yoke plates between which the upper ends are placed, thus providing means whereby the said link-members will be positively pivoted in position so as to insure accurate work 40 being done with the tool; thirdly: to so pivot the socket members to the lower end of the legs, and the lower end of the link members to said socket members, that a larger and stronger link member may be 45 used than is now ordinarily the case, and which can be almost completely housed within the legs; fourthly: to place the pivots of the legs and link-members where they are associated with the socket-members under 50 tension so as to keep these parts at their pivoted points from getting loose; fifthly: to provide the pivot holes in the lower end of each leg with recesses or pockets whereby the pivots uniting the same to the socket

members will always wear to a bearing. If 55 desired, a suitable lubricant, such as wax, may be placed in the said recesses or pockets. Sixthly: to provide means carried by the socket members to take up side wear on the lower ends of the legs and the link-members, 60 and to so position the said means as to render substantially equal the pressure exerted by the same against the lower ends of the legs and the lower ends of the link-members; seventhly: to so pivot the lower ends 65 of the legs in the socket members so that the lower ends of the link-members, when the compass or dividers is opened out wide, can freely pass through the pivotal axis of the lower end of each leg, and eighthly, to 70 provide an improved construction of lead holder which will permit various sizes of a graphite pencil or other marking element to be used and firmly held in place, and broadly speaking, my compasses or dividers consists 75 of a pair of legs, the upper ends of which are associated together with a pair of yoke-plates and a spacing-member which are all united by a pressure-screw and nut, the yoke-plates being of particular construction 80 to allow the upper ends of the link-members associated with the legs to be pivoted therein after a particular manner; socket-members to which the lower ends of said legs, and link-members, are pivoted after a particu- 85 lar manner, means being provided to provide for the transverse wear on the pivot bearings for the lower ends of the legs and link-members, and further means being provided to provide for the lateral wear on the 90 lower ends of the legs and link-members, as hereinafter particularly set forth.

Figure 1 is a front side elevation of my tool. Fig. 2 is a vertical section on the line *a*—*b*, Fig. 1. Fig. 3 is, in part, a rear side 95 elevation of my tool, the handle being in section, and one of the legs longitudinally cut through. Fig. 4 is a front view, on an enlarged scale, of the yoke, showing the upper ends of the link-members in closed position. Fig. 5 is a vertical section on the line *c*—*d*, Fig. 4. Fig. 6 is an end elevation of the yoke. Fig. 7 is, in part, a side elevation of one of the socket members, on an enlarged scale, and a section on the line *e*—*f*, Fig. 3. 100 Fig. 8 is an elevation of the rear side of one of the socket members. Fig. 9 is a longitudinal section through a portion of one of 105

the socket members and the holder for the marking element. Fig. 10 is a longitudinal section through the tube of the marking-element holder, and details. Fig. 10^a is a bottom plan view of the tube of the marking element holder. Fig. 11 is a perspective view of the marking-element holder operating within the tube illustrated in Fig. 10. Fig. 12 is a cross section through the lower end of one of the legs, and Fig. 13 is a side elevation of the spacing members of the yoke. Fig. 14 is a side elevation of the upper end of the tube illustrated in Fig. 10, and Fig. 15 is a plan view of the upper end of the said tube.

In the drawings, like characters of reference indicate corresponding parts in each figure.

One of my chief improvements is to construct my compass or dividers so that the link-members and legs will be doubly pivoted at their pivoted lower ends: that is to say, in place of only providing a single pin or pivot for the pivotal points, certain bosses or lugs are stamped out in pairs, from portions of the socket members, to pivot the lower ends of the legs and link-members in place, and certain lugs or bosses are formed in the upper ends of said link-members and one of the yoke plates, these bosses or lugs, when positioned, being in alinement, thus positively and snugly pivotally anchoring the upper ends of each link-member in place: not only does this cheapen the construction, but it also enables me to save time in assembling the component parts of each tool.

The legs A and B are preferably tubular in shape, as shown in Fig. 12, and integrally formed therewith are pairs of disks *a* and *b*. Upon referring to Fig. 2 it will be noticed that these disks are so placed that one disk of each leg is positioned between the pairs of disks of the other leg. Positioned between the inner pair of opposing disks *a* and *b*, is a yoke which is composed of a spacing-member C and yoke-plates D and E.

F is a pin carried by the spacing-member C and which secures the said yoke-plates thereto. The spacing-member C is shaped as shown at 2, Fig. 13 (see dotted lines Figs. 3 and 4,) to provide room for the upper end 3 of the link-members 4 and 5. The upper end of each link-member is provided with a boss 6, and each boss 6 extends into a hole 7 formed in the yoke-plate E. In forming the bosses 6, a bedway 8 is formed in the upper end of each link-member, and resting in each of these bedways is a boss 9 formed in the yoke-plate D. It will be understood that the upper end of each link-member is pivoted on both sides by the bosses 6 and 9, resulting in the advantages before clearly set forth.

95 The pressure-screw 11 passes through the

pairs of disks *a* and *b* and through the parts composing the yoke. Upon referring particularly to the dotted lines in Fig. 5, it will be noticed that the spacing member C is thinner than the upper ends of the links 4 and 5. As shown clearly in Figs. 2 and 3, the upper ends of the legs A and B are provided with longitudinal slots 12. Now by means of the pressure-screw 11 and its nut 13, when this nut is screwed, the described construction of the upper end of each leg will permit the disks to laterally yield and as the said spacing member C is thinner than the upper ends of the legs 4 and 5, the yoke-plates will be moved so as to cause the upper ends of the link-members 4 and 5 to be gripped between the wings 15 and 14 of the said yoke-plates, and thus provide for the desired stiffness in the head of the tool, the yoke itself being held under the pressure of the screw 11. The yoke-plates D and E are cut away as shown at 16 so that only the upper ends of the said link-members will be subjected to the pressure of the pressure-screw 11.

Preferably integrally formed with the spacing-member C, is a bifurcated extension G. This extension extends into the housing H carried by the leaves I and J, through which the pressure-screw 11 passes. The upper ends of the members composing the extension G are provided with offset ends *i*, which, when the said extension is inserted within said housing, have spring contact therewith. The leaves I and J are provided with vertical slots J¹ and J² and horizontal slots K. In order to keep the said housing and leaves in their vertical position, a pin L shown in Fig. 1 is carried by each of the outer disks of the legs A and B. These pins operate in the slots K. The vertical slots are necessary to allow for the vertical movement of the leaves I and J when the legs of the compass are moved. The housing also serves as a handle for the instrument.

The lower end of each link-member 4 and 5 is provided with a hole 17 which passes transversely through the same. The socket-members are composed of a front-plate 18 with which are integrally formed sockets 19 and 20.

21 is a front plate and same is riveted at 22 to the socket 19. Formed in the plates 18 and 21, so as to be in alinement are bosses 23 and 24, which have the relative position shown in Fig. 7, and these bosses extend one into each side of the hole 17. The lower end of each leg is laterally cut away as shown at 25 (see Figs. 3 and 12) so as to provide an opening which is occupied by the lower end 26 of the link-member associated with each leg.

Formed in the plates 18 and 21 respectively, are bosses 27 and 28. These bosses

are of course in alinement and occupy the position shown in Fig. 7, and extend into the holes 29 formed in the lower end of each leg A and B. Upon referring particularly to Fig. 7, it will be seen that the bosses 27 and 28 are flush with the inner surface of the leg, and as the link-members are positioned within the legs, it is clear that when the tool is opened out wide, the lower end 5 of each link-member can move freely between the bosses 27 and 28. This construction enables me to provide a very strong link-member, because it has not to be weakened in any way as would necessarily 10 be the case were a pin used in place of the bosses 27 and 28: because if a pin were used, in order to prevent conflict between the lower ends of the link-members and the said pins when the legs are opened out 15 wide, these lower ends of the link-members would have to be notched: now by reason of the said bosses this is avoided. Each link-member is cut away as shown at 30, and resting in this cutaway portion is a 20 leaf-spring 31. This leaf-spring always contacts with its associated wall of the leg within which it is housed, and as a result the pressure is always exerted so as to cause the bosses 27 and 28 to wear to a bearing 25 always in one direction.

Upon referring to Figs. 3 and 7 it will be noticed that the holes 29 in the lower end of each leg are provided with pockets 32 opening thereto. Now these pockets 35 will naturally determine the direction of wear of the bosses 27 and 28 and so insure the same always wearing to a bearing. If desired, any suitable lubricant such as graphite or beeswax, may be placed in the 40 said pockets 32. The wider the legs are moved apart, until they reach an angle of substantially 90 degrees with each other, the greater will be the tension against the spring 31. It will be noticed that this 45 spring is curved, and that its ends are curved oppositely to its middle portion. When the spring 31 is at maximum tension the middle portion is somewhat flattened out which tends to cause its ends to 50 recede from each other, but at the same time the spring is bent more sharply near the ends which bend down into the recesses 321 thus bending to draw the ends of the spring toward each other and counteract the effect 55 of flattening out the said middle portion. An advantage results from this construction in that it permits the spring to be made to fit its position more snugly than if the recesses 321 were not used and the ends of 60 the spring were not curved as described.

Screwing through the plates 18 and 21 is a compensating screw 33, the function of which is to give the necessary lateral pressure against the lower ends of the legs A 65 and B and the link-members, and take up

any lateral wear at these bearing points. Whereas the spring 31 provides for the transverse wear on the bosses 23 and 24 and 27 and 28, the screw 33 provides for the lateral wear. I find that the spring 31 and 70 the cutaway portion 30 can be dispensed with in more expensive makes of compasses, where the bosses formed in the plates 18 and 21, and the lower ends of the legs A and B and link-members 4 and 5, are specially hardened. The compensating-screw 33 should be positioned in the angle formed by the lines 34 and 35 drawn, respectively, through the center of the bosses 24 and 28 and the center of the rivet 22. Upon referring particularly to Figs. 3 and 7 it is clear that the area of the legs A and B in contact with the plates 18 and 21 is greater than the area of the lower ends 26 of the link-members 4 and 5 in contact with the 75 bosses 23 and 24. Therefore the position of the said screw should be such that the pressure exerted thereby will be distributed between the pairs of bosses 27 and 28 and 23 and 24, so as to give the desired result. 80

Each end of the hole 17 formed in the lower ends 26 of the link-members 4 and 5 is countersunk, and it will be noticed upon referring to Figs. 2 and 7 that the bosses 23 and 24 are conical in shape having rounded 85 ends. So constructing these bosses enables me to form them without breaking the metal, they being necessarily punched deeply in order to span the space between the plates 18 and 21, and the lower ends of the links 90 due to the thickness of the metal forming the U-shaped portion of the legs.

As shown in Figs. 3 and 4, the upper ends of the link-members 4 and 5 are curved as 95 shown at 36, thereby enabling me to place 100 these parts in small compass, and so that they will not conflict with any of the other parts when the tool is closed up.

The needle point 37 is held in the sockets of one of the socket members, and the preferred form of device for supporting the graphite pencil or marking element is as follows: 38 is a tube the upper end of which is rounded as shown at 39 so as to fit the upper socket 20. From the point 40 to 110 the end of the tube, the same is provided with a longitudinal slot 41. 42 is a shoe having a curved inner surface 43 between which and the wall of the tube 38 is gripped the pencil 44. 45 is a leaf spring, preferably integrally formed with the shoe 42, this spring is passed within the lower socket 19, and the upper end thereof is provided with a tooth 46 which extends into the slot 47 formed in the tube 38. On each side of 115 the tooth 46 is formed a shoulder 48. These shoulders abut against the inner side of the tube 38 on each side of the slot 47 as shown at 49. The length of the shoe 42 and its 120 relative position in respect of the lower end 125

of the tube 38, and the shape of the spring 45 is such as to insure the lead 44 being gripped tightly in place. Of course when the spring 45 is in the position illustrated, 5 in Fig. 9, it is compressed by the socket 19.

Upon referring particularly to Figs. 3 and 4, it will be noticed that the pivot points for the upper ends of the link-members 4 and 5 are so located on the yoke 10 that lines passing through the center of the said pivotal points shall cross each other on the center of the pressure-screw 11. According to the position of the pivot points for the upper ends of the said link-members 15 as illustrated in Figs. 3 and 4, these said pivot points occupy a position of substantially 45 degrees above the central pivot 11. Positioning the pivot points as described enables me to give the link-members their 20 required movement.

I do not confine myself to the construction herein shown and described except in so far as that may be rendered necessary by the prior state of the art, and the terms of 25 my claims.

What I claim as my invention is:—

1. A compass or divider comprising a pair of legs united by a pivot in their upper ends, a yoke member associated with 30 the upper ends of the said legs and pivoted concentrically therewith, means connecting the yoke with the upper ends of the legs whereby the vertical axis of the said yoke is maintained in a position centrally be- 35 tween the positions of the two legs, marking elements pivoted to the lower ends of the legs, a link associated with each leg, each link being connected at its lower end with the marking element on its associated 40 leg and each link having its upper end pivotally connected to the said yoke at a point above and to one side of the central pivot thereof, the whole being so constructed that as the legs are moved the marking elements 45 will be held parallel.

2. A compass or divider consisting of a pair of chambered legs united by a pivot in their upper ends, a yoke member associated with the upper ends of the legs and pivoted 50 concentrically therewith, means connecting the said yoke with the upper ends of the legs whereby the vertical axis of the said yoke is maintained in a position centrally between the positions of the two legs, marking 55 elements pivoted to the lower ends of the said legs, a link mounted within each leg each link having its lower end connected to the marking element on its associated leg, the said links having their upper 60 ends eccentrically connected with the said yoke at points so located on the said yoke that lines drawn through the said points and the central pivot of the yoke shall form an angle 90 degrees with each 65 other at the said central pivot, the whole

being constructed so that as the legs are moved the marking elements will be held parallel.

3. In a compass or divider a pair of chambered legs each having an opening in 70 the side and a U-shaped chamber below said opening, a pivot uniting the upper ends of the said legs, marking elements pivoted to the legs at the lower ends of the said U-shaped portions, a link mounted within each 75 leg, the lower end of each link being disposed partly within the said U-shaped portion and connected pivotally with the marking element pivoted thereto and means as- 80 sociating the upper ends of the links with the upper ends of the leg so that as the legs are moved the marking elements will be held parallel.

4. A compass or divider comprising a pair of legs, the upper ends of the said 85 legs being pivotally united to form the head, a hollow handle having a yoke at its lower end and wings depending from the said yoke, said wings adapted to embrace the upper 90 ends of the legs, means connecting the said wings with upper ends of the legs whereby the said handle is maintained in a position centrally over the head of the instrument, a yoke disposed between the upper ends of the legs and pivoted concentrically there- 95 with, an extension from the said yoke be- 100 tween the head of the legs reaching upward into the said hollow handle and engaging the sides of the said hollow handle, marking elements on the lower ends of the legs and a link associated with each leg, each link having its lower end connected to the marking element on its associated leg and each link having its upper end pivotally 105 connected with the yoke between the upper ends of the legs, the whole being so constructed that as the legs are moved the marking elements will be held parallel.

5. A compass or divider comprising a pair of legs the upper ends of both said 110 legs pivotally united to form the head, a hollow handle having wings depending therefrom, said wings disposed to embrace the upper ends of the legs, means connecting these said wings with the upper ends 115 of the legs whereby the handle is main- 120 tained in a position centrally over the head of the instrument, a yoke member disposed between the upper ends of the legs and pivoted concentrically therewith, a bifur- 125 cated extension from the said yoke mem- 130 ber extending upward into the said hollow handle and having spring contact with the inside of the said hollow handle, marking elements on the lower end of the legs, and a link associated with each leg, each link having its lower end pivotally connected to the marking element on its associated leg and each link having its upper end pivotally 135 connected with the yoke member between

the upper ends of the legs, the whole being so constructed that as the legs are moved the marking elements will be held parallel.

6. A compass or divider comprising a pair of legs united by a pivot in their upper ends, a handle having wings depending from its lower end and disposed to embrace the upper ends of the legs, each of the said wings being provided with a vertical slot to permit motion on the central pivot of the heads of the legs, and each of said wings also having a horizontal slot, and a pin on the upper end of each leg to engage the horizontal slot in the adjacent wing of the handle, a yoke-member disposed between the upper ends of the legs, means connecting the said yoke with the said handle, marking elements on the lower ends of the legs and links connecting the said marking elements with the said yoke-member between the upper ends of the legs, the whole being so constructed that as the legs are moved the marking elements will be held parallel.

7. A compass or divider comprising a pair of legs united by a pivot in their upper ends, marking elements pivoted to the lower ends of the said legs, a link associated with each leg and having pivotal connection with the marking element on the lower end of its associated leg, means connecting the upper ends of the links with the upper ends of the legs, each link having a recess in the side and a spring in the recess of each link to produce tension of the pivotal connections of the said links, legs, and marking elements.

8. A compass or divider comprising a pair of legs united by a pivot in their upper ends, marking elements pivoted to the lower ends of the said legs, a yoke member associated with the upper ends of the legs and pivoted concentrically therewith, said yoke comprising two yoke-plates spaced apart, a link associated with each leg, each link having its lower end connected with the marking element on its associated leg and its upper end pivoted between the two said yoke-plates, means connecting the yoke with the upper ends of the legs whereby the vertical axis of the said yoke is maintained in a position mid-way between the positions of the two legs, means for clamping the said upper ends of the legs and yoke plate together so as to frictionally engage the upper ends of the links, the whole being so constructed that as the legs are moved, the marking elements will be held parallel.

9. A compass or divider comprising a pair of legs having a yoke-member associated with their upper ends, the said yoke-member comprising two yoke-plates spaced apart, a pivot uniting the upper ends of the legs and the said yoke-plates together, means connecting the yoke-member with the upper ends of the legs whereby they are

maintained in their proper relation to the said legs, marking elements pivoted to the lower ends of the legs and a link associated with each leg, each link having its lower end connected with the marking element on its associated leg and its upper end pivoted between the said two yoke-plates, and means for producing pressure on the said yoke-plates whereby they are caused to frictionally engage the upper ends of the links, the whole being constructed so that as the legs are moved the marking elements will be held parallel.

10. A compass or divider consisting of a pair of legs united by a pivot in their upper ends, a link associated with each leg, the said links having their upper ends connected with the upper ends of the legs, a marking element pivoted to the lower end of each leg and its associated link, each marking-element comprising two plates having their lower portions connected together and a pin joining said plates and adapted to cause pressure of the said plates on the lower ends of the link and leg to which they are pivoted, said pin being so located that the pressure produced by it shall be distributed between the said link and leg to which said marking-element is pivoted.

11. In compasses or dividers of that class having automatically parallelizing points, a leg, a link, means pivoting the upper ends of said leg and link together, a marking element socket member comprising two plates connected together at their lower ends, the upper portions of said plates being adapted to engage the lower ends of said leg and link, and a pin joining said plates at a point above where the said plates are connected together, said pin being adapted to produce pressure of the said plates on the lower end of the leg and link associated therewith, and being so located that the pressure produced by the said pin shall be distributed between the said leg and link, and a socket carried by one of the said plates to hold a marking-element.

12. A marking element holder for a compass consisting of a channeled or U-shaped member adapted to receive the marking element, a member having its upper end connected to the upper end of the channeled member and having its lower end normally disposed between the sides of the channeled member in contact with the marking element, and means whereby the said members are caused to press upon the marking element so as to frictionally hold the same.

13. A marking element holder for a compass consisting of a U-shaped or channeled member adapted to receive the marking element, a member disposed in opposing relation to the said channeled member and having its lower end normally disposed between the sides of the channeled member so as to
